(57) **CLAIM**

The ornamental design for a front end of motor vehicle body, as shown and described.

DESCRIPTION

FIG. 1 is a right, front perspective view of a front end of motor vehicle body showing our new design;

FIG. 2 is a right, rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The portions of the motor vehicle body shown in a de-emphasized faded out half-tone form shown throughout the drawing views are for illustrative and environmental purposes and form no part of the claimed design.
